(57) CLAIM

The ornamental design for a floor mat, as shown and described.

DESCRIPTION

The claimed floor mat is used to indicate that shoes are to be left on the mat and recites, "leave shoes here."

FIG. 1 is a front view of a floor mat showing my new design;

FIG. 2 is a side view of the floor mat of FIG. 1; and,

FIG. 3 is another side view of the floor mat of FIG. 1.

The sides opposite those shown in FIGS. 2 & 3 and the rear of the floor mat form no part of the claimed design.
